UNITED STATES PATENT OFFICE.

HOMER A. HERR, OF PHILADELPHIA, PENNSYLVANIA.

CASH-REGISTER.

SPECIFICATION forming part of Letters Patent No. 443,994, dated January 6, 1891.

Application filed May 5, 1890. Serial No. 350,587. (No model.)

To all whom it may concern:

Be it known that I, HOMER A. HERR, of the city and county of Philadelphia, and State of Pennsylvania, have invented an Improvement in Cash-Registers, of which the following is a specification.

My invention has reference to cash-registers; and it consists of certain improvements, which are fully set forth in the following specification, and shown in the accompanying drawings, which form a part thereof.

The object of my invention is to provide in a cash-register suitable mechanism for locking all of the keys or levers when the cash-drawer is open, locking all of the keys or levers which are not struck, and also locking the keys or levers struck against backward movement until a completion of their full stroke, suitable mechanism operated by the keys or levers for exposing or unlocking a movable part, which may be actuated by the operator to release the cash-drawer, means for throwing the signal-bell out of action, a lock to lock all of the keys or levers irrespective of the position of the cash-drawer, and a catch or lock for the indicators, whereby all of the actuating parts for the indicators except the one operated are automatically locked against displacement.

In the drawings, Figure 1 is a sectional elevation on line $x x$ of Fig. 2. Fig. 2 is a sectional elevation of my improved cash-register, taken on line $y y$ of Fig. 1. Fig. 3 is a plan view of one of the locking-frames. Fig. 4 is a plan view of the signal-bell. Fig. 5 is a front elevation of a portion of the mechanism of my improved cash-register with the framing removed. Fig. 6 is a plan view of the drawer and its locking mechanism. Fig. 7 is a perspective view of same. Fig. 8 is a cross-section of Fig. 7 on line $s s$; and Fig. 9 is a view similar to a portion of Fig. 1, showing a modified arrangement of locking mechanism.

A is the frame of the machine.

B are a series of pivoted levers or keys having the marks placed upon the finger-pieces b , and said levers pivoted to a common shaft B' .

C are two registering-wheels, the lower of which operates the upper one in the usual way. The lower registering-wheel is operated by a

pawl c , carried upon a secondary lever C' , and which latter is operated by the keys or levers B. The registering-wheels C are prevented from accidental rotation by means of 55 the spring-pawls C^2 .

D are a series of indicator-rods, one for each lever or key B, and adapted to rise upon the rear end of said levers or keys. These rods are secured at the upper part of the screens 60 D' , which are adapted to cover the marks upon the tablets D^2 . When these rods and their screens are raised, the tablets are exposed. These rods D are provided with projections $d d'$, pointing in opposite directions, 65 for the purpose of locking said rods in their normal positions or supporting them when raised. E is a sliding locking-plate for said rods D, and is guided in the frame A by guide-ways W, and is reciprocated by a bell-crank 70 E', provided upon its free arm with a loose pawl e.

N is a vertically-reciprocating arm, which is actuated by the movement of any of the levers B in the manner hereinafter described, 75 and when raised rocks the bell-crank E', causing a reciprocation of the locking-plate E, so as to draw it over the projections d' and lock all the rods D which have not been raised during the act of raising the particular rod 80 which is purposely being raised. A spring e' is employed to return the parts to their normal position, as shown in Fig. 1. The rod D, which is raised, has its projections d caught above the locking-plate E, and is thus held in 85 an elevated position. This construction prevents the accidental raising of two indicating-bars and indirectly acts as a lock to the accidental and subsequent operation of any of the levers B which should not have been 90 struck.

F is a frame, which is pivoted at F^2 to the main frame. This frame has upon its rear end a series of slots f , through which project downwardly-extending arms B^2 from the several levers B. These arms B^2 may be pivoted to the levers B or may be cast integral therewith. Whenever one of these arms B^2 is raised it also raises the frame F. Pivoted to the frame A on studs h at the rear of the 100 arms B^2 is a locking-frame H, which has a lower projecting edge H' , adapted to be thrust

above or below the projections B^3 on the lower ends of the arms B^2 . The upper portion of this locking-frame H is curved inward, as at H^2 , and is adapted to be moved by cam projections T , extending upon the rear of the arms B^2 . When any of the arms B^2 are raised, the frame H is oscillated and the lower edge H' is thrust above the projections B^3 of the arms of the levers B , which have not been raised, and this locks them against accidental displacement. To the locking-frame H is connected a link F' , the other end of which is hinged to a sliding lock G , carried by the frame F and adapted to be forced under projections B^4 of the arms B^2 of such levers as are actuated. The object of this is to insure every lever which has been struck completing its full registering movement. By this construction it will be seen that if two levers B were struck simultaneously and intentionally the lock G would be thrust under the projections B^4 corresponding to such levers as soon as such projections were raised clear of the projections corresponding to the remaining levers, and then if the finger were removed from one of the said levers a continued pressure upon the remaining lever would insure registration of both levers.

I is a pivoted lever, provided with rack-teeth i , and is connected by a loose link J with the frame F . The upper or free end of the locking-frame H is adapted to catch in the teeth i of the lever I , and this prevents the return of the locking-frame H until it is released by a full movement of the levers B . If the lever struck were lifted a short way, so that the frame H caught into the first notch or tooth, this would lock all of the other levers B and prevent any operation of the machine until the lever struck was moved its full stroke, which action would cause the frame F to be fully raised and the projection G' to strike the lever I in such a manner as to leave it to release the locking-frame H . The link J is made loose, so that when the frame F is raised there is no resistance to the action of the projection G' . The lever I is so weighted at I' that when oscillated in either direction it remains in such position until positively shifted. When the frame moves upward, the lever I above the frame H is raised, and when the parts return to their normal position, with the frame F down, the lever I is pulled down again by the action of the link J .

K is a pivoted locking-frame secured to the rear of the machine and adapted to be drawn over the rear ends of the lever B by a spring k . Connecting with this frame is a bar K' , which extends down toward the drawer L . When the drawer L is trust in, it moves the locking-frame K out of reach of the rear ends of the levers B ; but if the drawer should be open then said locking-frame K is pulled by the spring k into position to lock all of the levers B .

Secured to the side of the drawer is a pro-

jection q , which is adapted to be caught by a locking-bolt Q , adapted to be thrust downward by a finger, so as to release the catch q . The spring Q' may be employed to normally keep the bolt in locking position. Arranged above the bolt Q is a pivoted plate P , having an aperture p and pivoted to the main frame at P' . This plate is connected by a link O with the locking-frame H , so that when said locking-frame is positively moved by an operation of any lever or key B the plate P is moved so as to bring the aperture p over the end of the locking-bolt, enabling the operator to depress said bolt to release the drawer. The plate P may also have a projecting loop P^2 , adapted to catch upon the under side of a head on the locking-bolt Q , as clearly shown in Fig. 8, so that said bolt is positively locked against movement, except when said plate P is shifted.

The plate P is in effect a lever and has pivoted to it a bell-crank lever R , the lower arm R' of which is adapted to be struck by a pin S on the drawer L . This bell-crank lever is connected by a spring r with the plate P , so as to act upon said plate and yet permit of an independent movement. This spring-connection is designed to enable the plate P to be moved before the drawer is released, and also to enable the drawer to be pushed into a locking position. When the drawer is released, it is forced outward by a spring l .

V is a lock secured to the frame of the machine, and is adapted to be operated by a key t , the said lock being designed to lock the frame F , and thereby all of the levers in case the operator wishes to leave the machine in a condition in which it cannot be operated in his absence and in which the cash-drawer is locked. The action of this lock V in preventing the movement of the frame F will prevent the movement of any of the levers B , since the upward movement of any of said levers must lift the frame F .

M is the alarm-bell, and is made of any suitable construction, and its hammer is operated by a pivoted lever m , which is rocked by a trip M^2 on the under part of frame F .

M' is a screw which extends through the rear of the machine and may be moved into position and throw the lever m out of action to prevent the striking of the bell during the operation of the machine. This is for use when it is desired to avoid the constant ringing of the bell.

In place of the mechanism shown in Fig. 1 for locking or coupling two or more of the operating-levers together and for locking all of the levers except those struck against movement, a modification in Fig. 9 may be employed. In this construction I have a sliding locking-piece H^3 , corresponding to the locking-edge H' of Fig. 1, which is connected by a frame with the pivoted frame H , so that when said frame is oscillated the locking-edge H^3 is thrust above the various projections B^3 on the arms B^2 of these levers, which have

not been struck. The other mechanism is substantially the same as that previously described.

In many instances sales are made which are to be charged, and where no cash is directly placed in the cash-drawer. Again, payments are made in checks. Also, in some cases cash is paid out from the cash-drawer. In other cases cash is paid in without sales having been made, and, finally, the machines are sometimes operated to give change. To permit these various operations to be carried out and make the register clearly indicate and record such operations, I provide a series of supplemental indicating devices such as above specified for indicating the amount of purchases, and provided with such terms as "Charge," "Paid in," "Paid out," "Change," and "check," and provide therefor a series of registering devices having their surfaces marked consecutively with multiples of one, and a series of keys or levers with words similar to those on the supplemental tablets. These various keys or levers and the connecting mechanism are operated in substantially the manner described with reference to the other indicators and registering mechanism, the only difference being that they do not relate to specific amounts, and are usually used in connection with some of the other keys or levers, which actually indicate the amounts.

While I prefer the constructions herein set out, I do not limit myself to the details thereof, as they may be modified in various ways without departing from the spirit of my invention.

Having now described my invention, what I claim as new, and desire to secure by Letters Patent, is—

1. In a cash-register, the combination of a series of operating keys or levers, a pivoted frame adapted to be operated by any of the said levers or keys, a pivoted locking-frame adapted to lock all of the levers against movement except those struck, supported independently of the said frame, cams upon the various levers or keys for oscillating the said locking-frame upon being struck, a locking-piece adapted to lock the levers or keys struck, so that a further movement of either of levers struck will cause all of the levers originally struck to move together, the said locking-piece being carried by the first-mentioned frame, and a connection between the locking-piece and locking-frame, whereby both are simultaneously moved by the action of the key or lever struck.

2. In a cash-register, the combination of a series of keys or levers having portions at their inner ends provided with projections, a locking mechanism located under the rear ends of the levers or keys to lock two or more of said levers or keys together to insure a positive movement of two or more of such levers when simultaneously struck, consisting of a sliding locking-piece adapted to be forced under the projections of the key struck, and

means to raise said locking-piece simultaneously with the raising of the inner ends of the keys or levers, whereby each of the keys or levers is required to perform its full function, independent locking mechanism operated by the levers or keys struck to lock the keys or levers not struck against movement, and a connection between the two locking mechanisms, whereby both operate simultaneously.

3. In a cash-register, the combination of a series of keys or levers having portions at their inner ends provided with projections, a locking mechanism to lock two or more of said levers or keys together to insure a positive movement of two or more of such levers when simultaneously struck, consisting of a sliding locking-piece adapted to be forced under the projections of the key or lever struck, a pivoted frame upon which the sliding locking-piece is supported, operated by the keys or levers struck, and connections, substantially as set out, for operating the sliding locking-piece by the upward movement of the levers or keys struck, whereby each of the keys or levers struck is required to perform its full function, and registering devices and operating mechanism therefor actuated by the keys or levers.

4. In a cash-register, the combination of a series of operating keys or levers having projections at their inner ends, registering mechanism operated by the keys or levers, an oscillating locking-frame operated by the movement of any of the levers and adapted to be projected above the projections of all of the levers or keys except those struck, a locking-piece operated by the movement of the levers to be forced under the projections, and a lock to couple two or more of the levers which are struck together and force them both to move simultaneously.

5. In a cash-register, the combination of a series of operating keys or levers having projections at their inner ends, registering mechanism operated by the keys or levers, an oscillating locking-frame operated by the movement of any of the levers and adapted to be projected above projections of all the levers except those struck, a locking-piece operated by the movement of any of the levers to be forced under projections of the levers struck to lock or couple two or more of the levers which are struck together and force them both to move simultaneously, a frame carrying the locking-piece connected to and moving with the levers struck, and a connection between the oscillating frame and said locking-piece, whereby the said locking-frame and locking-piece simultaneously move the locking-frame to lock the levers not struck and the locking-piece to lock the levers which have been struck.

6. In a cash-register, the combination of a series of operating keys or levers having projections at their inner ends, registering mechanism operated by the keys or levers, an oscil-

lating locking-frame operated by the movement of any of the levers and adapted to be projected above projections of all the levers except those struck, a locking-piece operated by the movement of any of the levers struck and adapted to be projected under projections of said levers to lock or couple two or more of the levers which are struck together and force them to move simultaneously, a frame carrying the locking-piece connected and moving with the levers struck, a connection between the oscillating frame and said locking-piece, whereby the said locking-frame and locking-piece simultaneously move the locking-frame to lock the levers not struck and the locking-piece to lock the levers which have been struck, a pivoted ratchet-lever adapted to lock the locking-frame against a return movement until the keys or levers struck have been fully moved, and mechanism, substantially as set out, for causing said ratchet-lever to be thrust into or out of contact with said locking-frame at the beginning and ending of the movement of the levers struck.

7. In a cash-register, the combination of a series of keys or levers having a hanging arm or projection at their inner end, an oscillating locking-frame operated by the movement of any of the levers and adapted to be projected above the projections of all the levers except the ones struck, and provided with a pawl projection, and a pivoted locking ratchet-lever having notches in which the pawl catches for locking said oscillating frame from a return movement until it has moved the full limit of play given it by the operating-key, and movable parts operated by the lever struck to oscillate the ratchet-lever.

8. In a cash-register, the combination of a series of keys or levers, a frame common to all of the keys or levers and operated by one of them, an oscillating locking-frame to lock the levers not struck against movement, an automatic lock for said oscillating locking-frame, whereby on the operation of any key or lever said automatic lock holds the locking-frame from releasing the levers or keys from a return movement until after it has completed the full limit of its play, and a connection between the frame common to all of the keys and levers and the said automatic lock for the locking-frame.

9. In a cash-register, the combination of a registering mechanism, a series of operating levers or keys for operating said registering mechanism and provided with depending arms, a frame common to all of said arms and adapted to be moved by the operation of one or more of said levers, a pivoted locking-frame operated by a cam projection upon said arms and adapted to lock all of said arms against vertical movement except those of the levers struck, a locking-piece carried by the first-mentioned frame and adapted to lock two or more of the arms together when slightly raised, and a connection between the pivoted

locking-frame and the locking-piece, whereby both are simultaneously operated.

10. In a cash-register, the combination of a registering mechanism, a series of operating keys or levers for operating said registering mechanism and provided with depending arms, a frame common to all of said arms and adapted to be moved by the operation of one or more of said levers, a pivoted locking-frame operated by a cam projection upon said arms and adapted to lock all of said arms against vertical movement except those of the levers struck, a locking-piece carried by the first-mentioned frame and adapted to lock two or more of the arms together when slightly raised, a connection between the pivoted locking-frame and the locking-piece, whereby both are simultaneously operated, a lock to prevent backward movement of the pivoted locking-frame except when moved to its full extent, and a mechanical connection between the said locking device and the movable frame first mentioned, whereby the said locking device is thrown into action when the frame is down and out of action when the frame is raised.

11. In a cash-register, the combination of registering mechanism, a series of operating keys or levers therefor, a movable frame common to all of said keys or levers and adapted to be moved by the operation of any one or more of said keys or levers, and a lock to lock said frame against movement when it is desired to prevent the action of the machine.

12. In a cash-register, the combination of indicating mechanism, a series of operating keys or levers for operating said indicating mechanism, a movable frame common to all of the keys or levers and movable with each of said keys or levers, and a lock to lock said frame against movement, and thereby prevent the operation of the indicating mechanism.

13. In a cash-register, the combination of registering devices, operating parts for operating said registering mechanism and a signal-bell, a frame common to all of the operating parts for actuating said bell, an inclosing case, and a movable piece extending through the casing of the register, whereby said bell-trip may be thrown out of action when desired without impairing the operative function of the machine.

14. In a cash-register indicating mechanism, a series of rods therefor with a locking projection or shoulder, a series of operating parts or keys, one for each of said rods, a movable lock to lock the rods against movement, and thereby the keys also, except those whose keys or operating parts are struck, and mechanism, substantially as set out, for actuating said movable lock.

15. In a cash-register, the combination of indicating mechanism, a series of rods therefor having two sets of locking projections or shoulders, a series of operating parts or keys, one for each of said rods, a movable lock to lock the rods against movement except those

- whose keys or operating parts are struck, and a mechanical connection between said lock and various keys or operating parts, whereby the movement of any key is caused to operate 5 said lock.
16. In a cash-register, the combination of indicating mechanism, a series of rods therefor having two sets of locking projections or shoulders, a series of operating parts or keys, one for each of said rods, a movable lock to lock the rods against movement except those whose keys or operating parts are struck, a frame common to all of the keys or operating parts and adapted to be moved by any one or 10 more of said keys or parts, and a connection between said moving frame and the lock, whereby the operation of any key or part is caused to actuate the lock.
17. In a cash-register, the combination of indicating mechanism, a series of rods therefor having two sets of locking projections or shoulders, a series of operating parts or keys, one for each of said rods, a movable lock to lock the rods against movement except those 15 whose keys or operating parts are struck, a frame common to all of the keys or operating parts and adapted to be moved by any one or more of said keys or parts, and a trip-connection between said moving frame and the lock, 20 whereby the operation of any key or part is caused to actuate the lock when being depressed, but without effect upon the lock when rising.
18. In a cash-register, the combination of 25 registering devices, a series of operating keys or parts therefor, a cash-drawer, a locking-bolt for said cash-drawer, a movable part to lock said bolt against movement, and connecting mechanism between the keys or operating parts and said movable locking part, 30 whereby the operation of any key actuates the moving part for the purpose of permitting the movement of the locking-bolt.
19. In a cash-register, the combination of 35 registering devices, a series of operating keys or parts therefor, a cash-drawer, a locking-bolt for said cash-drawer, a movable part to lock said bolt against movement, and connecting mechanism between the keys or operating parts and said movable locking part, 40 whereby the operation of any key actuates the moving part for the purpose of permitting the movement of the locking-bolt, and mechanical devices, substantially as set out, 45 actuated by the cash-drawer when closed, for resetting the locking part to relock the bolt against movement.
20. In a cash-register, the combination of 50 registering mechanism, a series of keys or levers for actuating said registering mechanism, a movable frame actuated by either or all of said levers or keys, a cash-drawer, a locking-bolt to lock said cash-drawer, and a releasing mechanism for releasing the bolt to permit 55 its operation actuated by said movable frame.
21. In a cash-register, the combination of 60 registering mechanism, a series of keys or levers for actuating said registering mechanism, a movable frame actuated by either or all of said levers or keys, a cash-drawer, a locking-bolt to lock said cash-drawer, a releasing mechanism for releasing the bolt to permit 65 its operation actuated by said movable frame.
22. In a cash-register, the combination of 70 registering mechanism, a series of keys or levers for actuating said registering mechanism, a movable frame actuated by either or all of said levers or keys, a cash-drawer, a locking-bolt to lock said cash-drawer, a releasing mechanism for releasing the bolt to permit 75 its operation, actuated by said movable frame, consisting of a movable plate having an aperture adapted to be drawn over the locking-bolt, and a connection between said plate and the movable frame.
23. In a cash-register, the combination of 80 registering mechanism, a series of keys or levers for actuating said registering mechanism, a movable frame actuated by either or all of said levers or keys, a cash-drawer, a locking-bolt to lock said cash-drawer, a releasing mechanism for releasing the bolt to permit 85 its operation, actuated by said movable frame, consisting of a movable plate having an aperture adapted to be drawn over the locking-bolt, a connection between said plate and movable frame, and a giving connection between said movable plate and the cash-drawer, whereby said plate may be automatically reset to lock the locking-bolt when the drawer is closed.
24. In a cash-register, a series of keys, a frame common to all of said keys and moved 90 by the operation of any one of them, a drawer for holding the money, a movable part or plate above said drawer, which plate is operated by said frame, and a part adapted to be touched by the hand, covered or concealed by said plate, 95 so that on operating any key said plate is moved by mechanism connected with said frame exposing said part, the touching of which opens the money-drawer.
25. In a cash-register, a series of keys, 100 combined with a movable plate, a money-drawer, and a part adapted to be operated by the hand, concealed by said plate, so that on operating any key said plate shifts its position, allowing the finger free access to said 105 movable part to open the drawer.
26. The combination, in a cash-register, of 110 a series of keys or levers, a drawer, a drawer-holder, a supplemental drawer-releasing key or part for releasing the drawer by the operation of the hand, connecting mechanism between the various keys or levers of the machine, and a supplemental drawer-releasing part, whereby upon the operation of any key or lever the said drawer-releasing part is unlocked or released, whereby it may be operated by the hand to release the drawer.
27. The combination, in a cash-register, of 115 a series of keys or levers for registering amounts of cash paid in, a drawer, a supplemental drawer-releasing key or part adapted to be operated by the hand to release the drawer, a lock to hold the supplemental drawer-releasing key or part against movement and adapted to automatically lock the 120 supplemental key or part against movement upon closing the drawer and when the regis-

tering keys or levers are in their normal positions, and connecting mechanism between the various registering keys or levers and the lock for the supplemental drawer-releasing key or part, whereby upon operating any registering key or lever the said supplemental drawer-releasing key or part may be released for operation by the hand.

In testimony of which invention I have hereunto set my hand.
